UNITED STATES PATENT OFFICE.

FRED W. CASTLE, OF HUNTINGTON, WEST VIRGINIA.

AUTOMOBILE LICENSE TAG.

Application filed June 15, 1922. Serial No. 568,497.

To all whom it may concern:

Be it known that I, FRED W. CASTLE, a citizen of the United States, residing at Huntington, in the county of Cabell, State 5 of West Virginia, have invented certain new and useful Improvements in Automobile License Tags; and I do hereby declare the following to be a full, clear, and exact description of the invention, such as will enable others skilled in the art to which it 10 pertains to make and use the same.

This invention relates to new and useful improvements in devices for attachment to automobiles, and particularly to license 15 number tags.

One object of the invention is to provide a license number tag which will be simple and cheap to construct, and which will be durable and effective in operation.

Another object is to provide a device of this character which, while being formed from interchangeable parts, will not rattle, as the automobile passes over rough or uneven streets and roads.

Other objects and advantages will be apparent from the following description when taken in connection with the accompanying drawing.

In the drawing:

Figure 1 is an elevation of a license number tag made in accordance with the invention.

Figure 2 is a longitudinal central sectional view through the tag, on the line 2—2 of Figure 1.

Figure 3 is a transverse sectional view, through the tag, and longitudinally of one of the removable number plates, on the line 3—3 of Figure 1.

Referring particularly to the accompanying drawing, 10 represents the base or back plate of the tag, which is preferably formed from a sheet of suitable stiff metal having a transverse outwardly extending rib 11 at

each end, the same being clearly shown in cross section in Figure 2. Disposed longitudinally adjacent each longer edge of the base plate 10 is a strip of metal 12 whose cross sectional outline is like that of the ribs 11, the outer wing 12' of which rests on the face of the plate. The opposite ends of the inclined wings of each of the strips 12 are cut off obliquely, as shown at 13, to fit properly against the inclined inner faces of the transverse ribs 11, of the base plate.

Disposed transversely of the base plate are

the individual, and removable number plates 14, each having a number, letter, or other symbol pressed thereon. The opposite ends of the plates 14 are offset outwardly, as shown at 15, and are disposed beneath the longitudinal strips 12. It will be particularly noted that the inner wing 12" of each of the strips 12 does not lie snugly against the inclined portion of a plate 14, with the result that as the bolts 16, which are disposed through the strips 12, the ends of the plates 14, and the base plate 10, are tightened, the said inner wings of the strips will have a tendency to draw on the ends of the plates 14, so that there will be no loose engagement between the plates and strips, thus eliminating all rattling or chattering of the parts. This wedging engagement of the plates 14 and strips 12 is clearly seen in the sectional view Figure 3.

By means of the bolts 16, which secure the endmost of the plates 14 in position, slotted plates 17 are held to the rear of the base plate 10, for the reception of straps (not shown), by which the tag may be suspended from a suitable portion of an automobile. Additional bolt openings 18 are formed through the end portions of the ribs 11, for attaching the tag rigidly, and directly to an automobile.

It will be readily understood that with a construction, such as shown in the drawing, the plates 14 may be removed and rearranged in accordance with the number which is given by the automobile license clerk of a State, county, or city, thus obviating the manufacture of new plates each year. The only complete change will consist in replacing the extreme right-hand plate, which has pressed thereon the year number.

It will also be understood that the entire device may be made longer or shorter, according to the number of plates 14 it is desired to place thereon, to constitute the license number for the ensuing year.

The upper edge of the back plate 10 is cut away, between the ribs 11, and that of the outer wing of the upper plate or strip 12 is extended across the said edge of the plate 10, and into contact with the hangers or loops 17. This is clearly seen in Figure 3.

What is claimed is:

1. A license number tag including a base plate, longitudinal strips secured to the base plate, one side of said strips resting against the base plate, the other side being off-set

away therefrom, and a plurality of removable plates disposed transversely of the base plate and having their ends offset and wedgely clamped beneath the offset portion 5 of the strips.

2. A license number tag including a base plate, longitudinal strips secured to the base plate, the outer side of said strips resting against the base plate, the inner side being 10 offset away therefrom and a plurality of removable plates disposed transversely of the base plate and having their ends offset

to conform with the offset portions of the longitudinal strips and passing there beneath, and means for wedgely clamping the 15 plates between the longitudinal strips and the base plate.

In testimony whereof, I affix my signature, in the presence of two witnesses.

FRED W. CASTLE.
